UNITED STATES PATENT OFFICE.

AARON P. GOULD, OF CANTON, OHIO.

DENTAL CHAIR.

SPECIFICATION forming part of Letters Patent No. 634,084, dated October 3, 1899.

Application filed July 24, 1899. Serial No. 724,959. (No model.)

To all whom it may concern:

Be it known that I, AARON P. GOULD, a citizen of the United States, residing at Canton, in the county of Stark and State of Ohio, have invented certain new and useful Improvements in Dental Chairs; and I do declare the following to be a full, clear, and exact description of the invention, such as will enable others skilled in the art to which it applies to make and use the same.

My invention relates to certain novel improvements in dental chairs.

The objects of the invention are to simplify and improve the construction and increase the convenience of manipulation to the operator and conduce to the comfort of the patient.

To this end the invention consists in the construction, combination, and arrangement of the several elements of the device, as will be hereinafter fully described, and particularly pointed out in the appended claims.

In the accompanying drawings, Figure 1 is a perspective view of my improved dental chair. Fig. 2 is a longitudinal section, partly in elevation. Fig. 3 is a perspective detail of the swivel-socket and diagonal brackets. Fig. 4 is a front elevation of the same. Fig. 5 is a detail perspective view of one of the diagonal brackets. Fig. 6 is a similar view of the cross-head. Fig. 7 is a similar view of the cross-head and rocking lever. Fig. 8 is a detail perspective view of one corner of the chair body and seat. Fig. 9 is a similar view of a corner of the seat-frame. Fig. 10 is a front elevation, partly in section, of a corner of the chair and seat. Fig. 11 is a detail perspective view of the cylinder-head bracket. Fig. 12 is a similar view of the oil-cylinder. Fig. 13 is a vertical transverse section of the same.

In the drawings the same reference characters indicate the same parts of the invention.

A denotes the cylindrical pedestal or base, formed with a cylindrical extension *a* to receive the encompassing socket *B*, which revolves freely thereon and which may be locked against rotation by a set-screw. (Not shown.) This socket *B* is formed with vertical parallel arms *A*² and *A*³, to which are secured the parallel diagonal brackets *b* *b*, the inner faces of which are formed with the parallel grooves

*b*² *b*³. I have shown these diagonal brackets *b* *b* formed with a lateral stud *b*^x, which extends through an orifice in the contiguous parallel arm, and with a horizontal lug *b*², which is secured by a bolt to the annular flange of the socket; but it is evident that, if desired, these brackets may be cast integral with the arms.

E denotes the cross-head, and it is formed with parallel tongues *b*¹ *b*¹, which have a sliding engagement with the grooves *b*² *b*³ in the brackets *b* *b*.

C denotes a forwardly curved arm fulcrumed at its lower end on a pin *c*, fixed in the outer ends of the socket-arms *A*² and *A*³, and *D* denotes a rocking lever fulcrumed on the rod *d*, transversely fixed in the arm *C*, and its lower end is bifurcated and pivoted on the pins *e* *e* in the cross-head *E*, while its upper end is pivoted to a rod *f*, which in turn is pivoted to a superimposed and rearwardly curved arm *K*, the lower end of which is fulcrumed in the forward end of the lower arm *C*.

H designates an oil well or chamber fixed within the socket *B*, and within said well is fixed an oil-cylinder *I*, in which is mounted a reciprocating plunger *E*³, the connecting-rod *f*¹ of which is pivoted to the bracket *E*⁴, fixed to the arm *C*.

*E*² denotes a hydraulic-jack cylinder, the piston of which is operated by the foot-lever *G*, there being a suitable valved connection between the cylinder *I* and the hydraulic-jack cylinder *E*², where the oil will be drawn from the oil-well *H* and forced into the cylinder *I*, causing it to raise the plunger *E*³ and thus elevate the forward end of the arm *C*, which carries with it the rocking lever *D*, the lower end of which draws the cross-head *E* up the inclined grooves in the stationary arms *A*² *A*³, and thus preserves the relative horizontal arrangement of the free ends of the arms *C* and *D*.

F denotes the seat-supporting frame, which is pivoted on the upper end of the arm *K*, and it is formed with parallel side rails *R* to receive the rollers *S*, mounted in the depending brackets *S*¹, formed integral with the chair-seat frame *S*².

The operation is as follows: When the lever *G* is reciprocated, the hydraulic-jack cylinder *E*² draws a small quantity of oil from the oil-

well II and forces it into the cylinder I under the plunger E³, causing it to rise a short distance in its cylinder I. This movement by the connection with the arm C by the rod f causes said arm C to move about its fulcrum-point in the socket B, raising the point of pivotal connection d with the lever D. The lower end of said arm D is in turn pivoted to the cross-head E, which has a sliding engagement with the parallel brackets A² A³ in the socket B. The lever D will thus be raised at its point of pivotal connection with the arm C, and its lower end, having a pivotal connection with the cross-head at e e, will slide forward and slightly upward in a straight line, as determined by the grooves b² b³ in the parallel brackets b b. This movement causes the free end of the lever D to move in the arc of a circle and, being connected by the rod f to the arm K, causes said arm to move about its pivotal connection with the arm C, thus keeping the upper end of said arm K and the chair-seat approximately horizontal and parallel with the floor.

25 The rear end of the chair-seat frame is pivoted to the curved arm t of the back-supporting bracket T, the bifurcated arms t t' of which are pivoted to the seat-supporting frame by the rivets t', as shown in Fig. 2.

30 A spring-actuated lever P is provided with a pawl p, which engages the rack-teeth p', formed on the curved arm t, the operation being such that when the back-supporting arm T is moved forward the seat-frame S² will be drawn rearward, and, vice versa, the rearward movement of the back-rest will carry the seat forward.

It will of course be understood that various changes in the form, proportion, and the minor details of construction may be resorted to without departing from the principle or sacrificing any of the advantages of this invention.

Having thus described the invention, what is claimed, and desired to be secured by Letters Patent, is—

1. The combination in a chair structure, of a base and a body portion; two superimposed arms or levers hinged together at their forward ends, the free end of the upper arm connected to the body portion, a swinging bar pivoted intermediate of its ends to the lower arm, a connection between the upper end of

said swinging bar and an intermediate portion of the upper arm, a cross-head pivoted to the end of the swinging bar and having a sliding connection with the base; means for raising and lowering said arms, and means for sustaining said chair-body in the adjusted positions, substantially as described. 55

2. The combination in a chair structure, of a base and a body portion, an intermediate body-support consisting of two superimposed arms hinged together, one arm being hinged to the base and the other connected with the body portion, a beam or lever pivoted to the lower arm, the lower end of said lever or beam being connected to the base to move in a straight line, a connection between the upper end of said lever or beam and the upper arm 65 to transmit the movement of the lower to the upper arm, means for raising and lowering the said arm, and means for sustaining the body portion in adjusted positions, substantially as described. 70

3. The combination in a chair structure, of a base and a body portion, a socket revolvably mounted on said base and formed with parallel arms, grooved brackets mounted on said arms, a forwardly-curved arm fulcrumed between said parallel arms, a lever fulcrumed in said curved arm, and a cross-head pivoted to the lower end of said lever and having a sliding engagement with said grooved arms, substantially as and for the purpose set forth. 75

4. The combination in a chair structure, of a base and a body portion, a socket revolvably mounted on said base and formed with parallel arms, grooved brackets mounted on said arms, a forwardly-curved arm fulcrumed between said parallel arms, a lever fulcrumed in said curved arm, and a cross-head pivoted to the lower end of said lever and having a sliding engagement with said grooved arms, a rearwardly-curved arm fulcrumed at its forward end to said forwardly-curved arm, and a rod pivotally connecting said rearwardly-curved arm and the forward end of said lever, substantially as and for the purpose set forth. 95

In testimony whereof I have hereunto set my hand in presence of two subscribing witnesses.

AARON P. GOULD.
